UNITED STATES PATENT OFFICE

2,047,981

ROCK DRILL

Charles F. Osgood, Claremont, N. H., assignor to
 Sullivan Machinery Company, a corporation of
 Massachusetts

Application November 1, 1934, Serial No. 751,020

15 Claims. (Cl. 121—9)

This invention relates to rock drilling mechanisms, and more particularly to improvements in the feeding and guiding means for a rock drill of the mounted "drifter" type.

An object of this invention is to provide an improved rock drill feeding mechanism. Another object is to provide an improved feeding means for a rock drill of the mounted, self-feeding, "drifter" type. A further object is to provide an improved pneumatic feeding means for a rock drill whereby a feed of comparatively great length is obtained by means of a relatively compact feeding structure and having improved transmission connections between the power feeding elements and the drill whereby such compactness is possible. Yet another object is to provide improved fluid sealing means associated with the transmission connections and feeding elements whereby fluid leakage from the feeding cylinders is reduced to a minimum. Yet another object is to provide improved flexible force transmitting connections between the power feeding elements and the drill and with which the improved fluid sealing means is associated whereby leakage of fluid from the feed cylinders past the flexible connections and the necessity of packing the flexible connections are entirely eliminated. A further object is to provide an improved pneumatic feeding mechanism and guide structure for a rock drill of the mounted "drifter" type. These and other objects and advantages of the invention will, however, hereinafter more fully appear.

In the accompanying drawing there is shown for purposes of illustration one form which the invention may assume in practice.

In this drawing,—

Fig. 1 is a top plan view of the illustrative embodiment of the improved rock drilling mechanism.

Fig. 2 is a side elevational view of the rock drilling mechanism shown in Fig. 1, parts being shown in longitudinal section to illustrate structural details.

Fig. 3 is a front end elevational view of the rock drilling mechanism shown in Figs. 1 and 2.

Fig. 4 is an enlarged longitudinal sectional view taken substantially on line 4—4 of Fig. 2, with parts omitted.

Fig. 5 is a cross sectional view taken on line 5—5 of Fig. 1.

Fig. 6 is a cross sectional view taken substantially on line 6—6 of Fig. 2.

Fig. 7 is a diagrammatic view of two parts of the control valve.

As shown in the drawing, the improved rock

drilling mechanism is of the mounted "drifter" type, although it will be evident that the improved structure constituting the features of this invention may be incorporated in drills of various other types.

The drilling mechanism disclosed herein comprises a hammer rock drill generally designated 1 supported by and guided for longitudinal movement on a feeding and guiding structure generally designated 2 of an improved design. As shown herein, the hammer drill 1 may assume any usual form and is herein preferably of the pressure fluid actuated, hammer type having a usual hammer motor for percussively actuating, in a well known manner, a drill steel 3 suitably supported within the forward end of the drill. The improved guide and feed structure 2 comprises a pair of parallel feed cylinders 4 and 5 spaced transversely by end spacing and connecting elements 6 and 7 and supported upon a suitable bracket 8 carried by a swivel trunnion 9, the end spacing and connecting elements 6 and 7 being secured to the cylinders and the cylinders being rigidly secured to the bracket 8 in any suitable manner, such for instance as by welding. The hammer drill 1 is supported directly on and between the parallel cylinders 4 and 5 by the provision of a depending portion 10 integral with the drill bottom which may be of any suitable longitudinal length so as to provide a sufficient bearing surface, while a clamping element 11 is removably secured to and spaced from the depending portion 10 as by screw bolts 12 and shims 13. The elements 10 and 11 present concave bearing surfaces 14 slidably engaging the adjacent inner portions of the peripheries of the parallel cylinders 4 and 5. As the bearing surfaces wear, the shims 13 may be varied in thickness and the wear taken up. It will thus be seen that the hammer drill is entirely supported by the parallel feed cylinders without the use of any other elements, thereby causing the feed cylinders to perform all the functions of the usual guide shell. Reciprocable in the cylinders 4 and 5 are feed pistons 15 and 16, respectively, the piston 16 constituting the forward feed piston and the piston 15 constituting the reverse feed piston. Secured by an element 17 threaded within the body of the feed piston 15 is a flexible element 18 herein in the form of a wire rope or cable, and this cable extends forwardly through the forward portion of the feed cylinder 4, through an opening 19 in the front head 20 of that feed cylinder, around a pulley 21 secured by a bracket 22 integral with the connecting ele-

ment 6, and then rearwardly for connection to the drill 1 by an adjustable element 23 threaded within the forward portion of the drill guide member 11. Secured by a member 24 threaded within the body of the feed piston 16 is a flexible element 25, herein a wire rope or cable extending rearwardly through the rearward portion of the feed cylinder 5, through an opening 26 in the rear feed cylinder head 27, around a pulley 28 carried by a bracket 29 integral with the connecting element 7, and then forwardly for connection to the drill 1 by an adjustable member 30 threaded within the rearward portion of the drill guide member 11. Arranged parallel with the feed cylinders 4 and 5 with its axis lying in a vertical plane midway between the feed cylinders but offset downwardly therefrom is a tubular member 31 herein extending co-extensively with the feed cylinders and supported in spaced relation with respect to the cylinders within aligned bores 32 formed in the spacing and connecting elements 6 and 7. This tubular member is formed with its end portions reversely bent in opposite directions at 33 and 34, respectively, in U-shaped form, and the reversely bent portions of this member project within bores 35 formed in the front and rear heads 36 and 37, respectively, of the feed cylinders 5 and 4, and each is held in sealed relation thereto by means of a packing 38 held in compression in engagement with the exterior periphery of the tubular member by adjustable plugs 39 threaded within the cylinder heads 36 and 37. This tubular member is preferably composed of two cooperating parts to facilitate assembly, and the bore 32 in the connecting element 6 is packed to seal tightly the joint, although any suitable "union" form of connection could be resorted to. Reciprocably mounted within the bore of the tubular member 31 is a sealing element herein in the form of a piston 40 comprising a body element 41 having secured thereto, as by clamping elements 42, oppositely directed cup packings 43, the elements 42 being held in position on the piston body by means of eye-bolts 44 threaded within the opposite ends of the piston body 41. These adjustable eye-bolts 44 are respectively connected to the adjacent ends of flexible transmission elements 45 and 46 each in the form of a roller chain of the block type. As shown in Fig. 4, these roller chain sections are connected to the opposite ends of the feed pistons 15 and 16, respectively, and the other ends of these chains are adjustably connected to the body element 41 of the sealing piston 40 by means of the eye-bolts 44. The connections of these roller chain sections with the feed pistons 15 and 16 each comprise an eye-bolt 47 threadedly secured within the body of each feed piston. These chain sections extend in opposite directions rearwardly and forwardly through the opposite ends of the feed cylinders 4 and 5, and the forward chain section is guided by the rollers thereof on the inner curved surface 48 of the forward bent portion 33 of the tubular member 31, and extends through the tubular member 31 into connection with one end of the sealing piston 40, while the rearward chain section 46 extends and is guided in a similar manner about the rear bent portion 34 of the tubular member 31 and through this member into connection with the opposite end of the sealing piston 40. By adjustment of the connections of the flexible elements 18 and 25 and the chain sections 45 and 46 with the feed pistons and the drill guide member 11 the ropes and chain sections are maintained under

the desired tautness. It will thus be seen that the forward end of the feed cylinder 4 and the rearward end of the feed cylinder 5 open directly to atmosphere through the openings 19 and 26, while the rear end of the feed cylinder 4 and the forward end of the feed cylinder 5 open directly within the tubular member 31 within which the sealing piston 40 is mounted. This sealing piston 40 prevents substantial leakage of fluid from the opposite ends of the feed cylinders 10 through the tubular member past the sealing piston.

Now referring to the means for controlling the flow of pressure fluid to the feeding cylinders, it will be noted that formed integral with the cross connection 7 at the rear ends of the feed cylinders 4, 5 is a valve casing 50 having a bore 51 containing a control valve 52 having a usual operating handle 53. Pressure fluid is supplied from any suitable source to the interior of the valve 20 through a pipe connection 54. The rear end of the feed cylinder 4 is connected to the valve bore through a passage 55, while the valve bore is connectible to the forward end of the feed cylinder 5 through a passage 56 extending across the connection 7 and a communicating pipe connection 57 extending longitudinally along the outer side of the feed cylinder 5. When the valve 52 is in the position shown in Fig. 4, pressure fluid may flow through passage 55 to the rear end of the feed cylinder 4 to act on the rear pressure area of the feed piston 15, thereby to effect through the chain section 46, chain section 45 and wire rope 25 rearward feed of the rock drill along the guiding surfaces of the parallel cylinders, the forward end of the feed cylinder 5 being suitably vented to atmosphere at that time through pipe 51, passage 56, a suitable valve groove 58 and a port 59. When the valve 52 is turned into its other flow providing position, pressure fluid may flow through passage 56 and pipe 57 to the forward end of the cylinder 5 to act on the forward pressure area of the feed piston 16, thereby to effect, through the chain section 45, the chain section 46 and wire rope 48, forward feed of the rock drill along the guiding surfaces of the feed cylinders, the rear end of the feed cylinder 4 being suitably vented to atmosphere at that time by a groove 60 and port 61. In the intermediate position of valve 52 both passage 55 and passage 56 are connected to atmosphere, the exhaust grooves in the valve both connecting with their respective ports 55 and 56 in "mid" valve position. Of course as the feed pistons 15 and 16 reciprocate in the feed cylinders, the sealing piston 40 reciprocates within the sealing cylinder formed by the tubular member 31, the sealing piston moving in a direction opposite from the direction of movement of the active feed piston so that the active flexible elements are at all times maintained sealed with respect to the active feed cylinder.

As a result of this invention, it will be noted that an improved rock drill feeding mechanism is provided wherein a relatively long feed is attained without materially increasing the overall dimensions of the feeding and guiding structure. It will further be noted that an improved rock drill feeding mechanism of the pneumatic type is provided having improved flexible transmission means between the power feeding elements and the rock drill, and improved sealing means associated with the transmission means and feeding elements whereby fluid leakage is reduced to a minimum. It will still further be evident that

5 by the provision of the improved feeding and guiding structure the rock drill is supported and guided in an improved manner, and that by the association of the feeding elements with the guiding structure and by guiding the drill directly on the feed cylinders the drilling mechanism is rendered extremely simple in design, and by its simplicity results in a mechanism which is of a more rugged character and relatively inexpensive to manufacture. These and other uses and advantages of the improved drilling mechanism will be clearly apparent to those skilled in the art.

10 While there is in this application specifically described one form which the invention may assume in practice, it will be understood that this form of the same is shown for purposes of illustration and that the invention may be modified and embodied in various other forms without departing from its spirit or the scope of the appended claims.

15 What I claim as new and desire to secure by Letters Patent is:

20 1. In a rock drilling mechanism, parallel feed cylinders, feed pistons reciprocable therein, a tubular member connected to said cylinders, a rock drill, a sealing piston reciprocable in said tubular member, flexible transmission elements connecting said feed pistons to said sealing piston, and flexible transmission elements connecting said feed pistons with the rock drill.

25 2. In a rock drilling mechanism, a rock drill, parallel feed cylinders, feed pistons reciprocable therein, a sealing cylinder connected to said cylinders, a sealing piston reciprocable in said sealing cylinder, transmission elements connecting said feed pistons to said sealing piston, and flexible transmission elements connecting said feed pistons to said rock drill.

30 3. In a rock drilling mechanism, parallel feed cylinders, a parallel tubular member connected to said cylinders, elements connecting the opposite ends of said feed cylinders and tubular member in rigid spaced relation, a rock drill, feed pistons reciprocable in said feed cylinders, a sealing piston reciprocable in said tubular member, flexible transmission elements connecting the opposite ends of said sealing piston with said feed pistons, and flexible transmission elements connecting opposite ends of said feed pistons to the opposite ends of said drill.

35 4. In a rock drilling mechanism, a pair of parallel single-acting feed cylinders each having an end to which actuating pressure is adapted to be supplied, a tubular member arranged parallel with said feed cylinders and connected to and communicating with said ends of said cylinders, means connecting said feed cylinders and said tubular member in rigid spaced relation, a rock drill, feed pistons reciprocable in said feed cylinders, a sealing piston reciprocable in said tubular member and providing a separating wall for preventing communication between said ends of said cylinders, flexible transmission means extending within said tubular member for connecting said feed pistons to said sealing piston, and flexible transmission means for connecting said feed pistons to said rock drill.

40 5. In a rock drilling mechanism, parallel feed cylinders, a parallel tubular member, elements connecting the opposite ends of said feed cylinders and tubular member in rigid spaced relation, said tubular member communicating at one end with one end of one feed cylinder and at its opposite end with the opposite end of the other

45 feed cylinder, a rock drill, feed pistons reciprocable in said feed cylinders, a sealing piston reciprocable in said tubular member, flexible transmission means connecting said feed pistons to said sealing piston, and flexible transmission means connecting said feed pistons to the rock drill.

50 6. In a rock drilling mechanism, parallel feed cylinders, a rock drill guided for movement longitudinally of said cylinders, a tubular member extending longitudinally between said feed cylinders and having reversely bent front and rear end portions, the front portion of said tubular member communicating with the forward end of one feed cylinder and the rear portion of said tubular member communicating with the rear end of the other feed cylinder, feed pistons reciprocable in said feed cylinders, a sealing piston reciprocable in said tubular member, connections between said feed pistons and said sealing piston, said connections extending within said tubular member into connection with the opposite ends of the sealing piston and guided by the inner surfaces of the reversely bent portions of said tubular member, and connections between said feed pistons and the rock drill.

55 7. In a rock drilling mechanism, a rock drill, parallel feed cylinders, pistons reciprocable in said feed cylinders, a conduit connecting one end of one feed cylinder to the opposite end of the other feed cylinder, means for connecting said feed pistons with the rock drill, a sealing means arranged within said conduit, and means for connecting said feed pistons to said sealing means.

60 8. In a rock drilling mechanism, a rock drill, parallel feed cylinders, pistons reciprocable in said feed cylinders, a conduit connecting one end of one feed cylinder with the opposite end of the other feed cylinder, said conduit having a portion arranged parallel with and extending longitudinally between said feed cylinders, means connecting said feed pistons to the rock drill, a sealing piston reciprocable within said longitudinal parallel portion of said conduit, and means connecting said feed pistons with said sealing piston.

65 9. In a rock drilling mechanism, the combination with a rock drill to be fed, of parallel single-acting feed cylinders each having an end to which actuating pressure is adapted to be supplied, feed pistons reciprocable in said cylinders, a tubular member connected to said cylinders in communication with said ends of said cylinders, a sealing piston reciprocable in said tubular member and providing a separating wall for preventing communication between said ends of said cylinders, flexible transmission means extending within said tubular member for connecting said feed pistons to said sealing piston, and flexible transmission means connecting said feed pistons to said rock drill.

70 10. In a rock drilling mechanism, the combination with a rock drill to be fed, of parallel feed cylinders each having an open end, a tubular member arranged parallel with said cylinders and connected to the opposite ends of said cylinders, means connecting said feed cylinders and tubular member in rigid spaced relation, feed pistons reciprocable in said feed cylinders, a sealing piston reciprocable in said tubular member and providing a separating wall for preventing communication between said ends of said cylinders with which said tubular member is connected, flexible

75

transmission means extending within said tubular member for connecting said feed pistons to said sealing piston, and flexible transmission means connecting said feed pistons to said rock drill and having portions extending out through said open ends of said feed cylinders.

11. In a rock drilling mechanism, the combination with a rock drill to be fed, of parallel feed cylinders, one cylinder having an open front end and the other cylinder having an open rear end, a tubular member arranged parallel with said feed cylinders and communicating with the opposite ends of said cylinders, said tubular member communicating at one end with the front end of one feed cylinder and at its opposite end with the rear end of the other cylinder, feed pistons reciprocable in said feed cylinders, a sealing piston reciprocable in said tubular member and providing a separating wall between said ends of said feed cylinders with which said tubular member communicates, flexible transmission means extending within said tubular member for connecting said feed pistons to said sealing piston, and flexible transmission means connecting said feed pistons to said rock drill and having portions extending out through said open ends of said feed cylinders.

12. In a rock drilling mechanism, the combination with a rock drill to be fed, of parallel feed cylinders, one cylinder having an open front end and the other cylinder having an open rear end, a tubular member extending longitudinally between said feed cylinders in parallel relation therewith and having reversely bent front and rear end portions communicating with the opposite ends of said cylinders, the front end portion of said tubular member communicating with the forward end of one feed cylinder and the rear end portion of said tubular member communicating with the rear end of the other feed cylinder, feed pistons reciprocable in said feed cylinders, a sealing piston reciprocable in said tubular member and providing a separating wall between the ends of said feed cylinders with which said tubular member communicates, connecting means between said feed pistons and said sealing piston including means extending within said tubular member into connection with the opposite ends of said sealing piston and guided by the inner surfaces of said reversely bent end portions of said tubular member, and connecting

means between said feed pistons and said rock drill including connections extending out through said open ends of said cylinders.

13. In a rock drilling mechanism, parallel feed cylinders each having an open end, a rock drill, feed pistons reciprocable in said feed cylinders, means for connecting said feed pistons to said rock drill and including connections extending out through said open ends of said feed cylinders, and means for sealing the opposite ends of said feed cylinders including a conduit communicating with the sealed ends of said feed cylinders, sealing means arranged within said conduit and providing a separating wall for preventing communication between the sealed ends of said cylinders, and means extending within said conduit and into the sealed ends of said feed cylinders for connecting said feed pistons to said sealing means.

14. In a rock drilling mechanism, parallel feed cylinders each having an open end, a rock drill, feed pistons reciprocable in said feed cylinders, means connecting said feed pistons to said rock drill and including means extending out through said open ends of said feed cylinders, and sealing means for the opposite ends of said feed cylinders including a conduit communicating with the sealed ends of said cylinders, said conduit having a portion arranged parallel with and extending longitudinally between said feed cylinders, sealing means reciprocable within said longitudinal parallel portion of said conduit and providing a separating wall for preventing communication between the sealed ends of said cylinders, and means extending within said conduit and into the sealed ends of said feed cylinders for connecting said feed pistons to said sealing means.

15. In a rock drilling mechanism, parallel feed cylinders, a parallel tubular member, elements connecting the opposite ends of said feed cylinders and tubular member in rigid spaced relation, said tubular member communicating at one end with one end of one feed cylinder and at its opposite end with the opposite end of the other feed cylinder, a rock drill, feed pistons reciprocable in said feed cylinders, sealing means reciprocable in said tubular member, connections between said feed pistons and said sealing means, and connections between said feed pistons and said rock drill.

CHARLES F. OSGOOD.
